MANUALLY CENTERED LINE BORING MACHINE

Edward A. Foster, Borger, Tex.

Application November 16, 1948, Serial No. 60,315

1 Claim. (Cl. 77—2)

1 My present invention relates to the general class of portable, manually operated boring machines, and more specifically to a manually centered line boring machine which, while well adapted for various purposes and uses, is especially designed for accuracy in boring the spaced bearings of motors or engines. The primary purpose of the invention is the provision of a manually operated line boring machine of the portable type having means whereby the boring bar may readily be adjusted in horizontal and vertical directions with a minimum expenditure of time and labor, and then rigidly supported in adjusted position for accurately boring the aligned bearings.

The invention includes a minimum number of parts, some of which are interchangeable, that may be manufactured with facility and low cost of production, and the parts may be assembled with convenience, to provide a reliable machine that may be installed for use with ease, and which performs its functions with precision.

The invention consists in certain novel features of construction and combinations and arrangements of parts that are embodied in each of two or more bridges, or bearing supports for the boring bar that make up the tool, and in their adjustment mechanisms as will hereafter be described and more particularly set forth in the appended claim.

In the accompanying drawings I have illustrated one of the bridges of the boring tool in which the parts are combined and arranged in accord with one mode I have devised for the practical application of the principles of the invention. It will however, be understood that changes and alterations are contemplated and may be made in these exemplifying drawings and mechanical structures, within the scope of my claim without departing from the principles of the invention.

Figure 1 is a view in end elevation of one of the bridges showing its relation to an engine block on which it is mounted; and Figure 2 is a top plan view of the structures in Fig. 1.

Figure 3 is an enlarged vertical sectional view at line 3—3 of Fig. 2.

Figure 4 is an end view of the bridge. Figure 5 is a vertical transverse sectional view at line 5—5 of Fig. 3; and Figure 6 is a similar view at line 6—6 of Figure 3.

Figure 7 is a perspective view of one of the two hold down blocks, or attaching blocks for the bridge.

In order that the general arrangement and

utility of parts of the portable boring machine may readily be understood I have indicated by dotted lines in Figs. 1 and 2, the lower section E of an engine block having bearings B that are to be bored; and the flanged portion F of the engine block is provided with the usual bolt holes for tie bolts that unite the lower and upper portions of the engine. These bolt holes are utilized in mounting and attaching two or more of the bridges of the boring tool, and the transversely arranged bridges are spaced longitudinally of the engine block to support the boring bar of the machine, which bar is usually turned by hand.

15 The cross bridge illustrated for supporting the adjustable and operating parts of the tool, includes two, laterally spaced and arched brackets 1 and 2, each having a pair of oppositely extending arms 3, 3, and 4, 4, and each of the arms, at 20 its inner side, is fashioned with a dovetail groove 5.

25 Each pair of arms is equipped with an interchangeable and adjustable hold down block, or attaching block 6 having dovetail tongues 7, 7, for sliding adjustment in the grooved pairs of arms; and the hold down blocks are separately adjustable in adapting the boring tool to motors or engines of varying widths.

30 By means of two hold down or attaching bolts 8, 8, that are passed through slots 9 of the blocks and threaded in the bolt holes of the flange F, the bridge may be rigidly fastened in operative position.

35 The usual boring bar with its tools, is adjustably mounted in aligned split bearings of the boring machine, one of which bearings is illustrated at 10, and provided with a clamping bolt 11 for mounting on the boring bar; and this resilient split bearing is integral with a vertical adjustable pilot post or bar 12 that is supported and suspended in an upright bushing 13. The bushing may rigidly be clamped upon the post by means of a pair of spaced clamp bolts 14, 14, and clamping keys 15, 15, that are retained on the reduced or pin ends of the clamp bolts.

40 For vertically adjusting the post and centering the boring bar the upper end of the post is threaded at 16, preferably with square threads, and a knurled open end adjusting nut or threaded sleeve 17 threaded on the post, is screwed down against the upper end of the bushing.

45 For laterally and horizontally adjusting the pilot post and the boring bar mounted therein, a pair of opposed and axially aligned, interchangeable screw bars or bolts 18 and 19, at their inner

ends 20 are threaded, permanently, in diametrically arranged sockets of the bushing 13. These bolts or screw bars, rigid with the bushing, are transversely adjustable transversely of the engine block, and for this purpose they are mounted between the spaced arched brackets, in transversely arranged spacing blocks 21 and 22 that are rigidly fastened to the arches 1 and 2 by bolts 23 and 24, the latter extending through the blocks and the arches and provided with lock nuts 25.

For laterally adjusting the pilot post and centering the boring bar, two opposed threaded bushings or hand-turned nuts 26 and 27 are threaded on the outer ends 28 of the screw bars, and each bolt or screw bar is rigidly clamped within its block in adjusted position by means of a clamp bolt or set bolt 29 threaded down through the block and provided with a reduced end or dowel pin 30 upon which a clamp key 31 is mounted for engagement with the threads of the 20 screw bar.

Thus by manipulating the nut 17 for vertical adjustment and the opposed nuts 26 and 27 for horizontal or lateral adjustment, the pilot posts 25 may easily be centered with the boring bar mounted therein, for precise arrangement of the mounted boring tools on the boring bar; and the manually operated boring bar performs its functions with efficiency and facility.

Having thus fully described my invention, what

I claim as new and desire to secure by Letters Patent is:

A portable cross bridge for supporting an adjustable tool comprising two laterally spaced arched brackets, a pair of oppositely extending arms on each bracket, a pair of screw bars mounted between the bracket in opposed relation to each other, a bushing threaded to the inner ends of the screw bars for supporting a pilot post, spacing blocks on the brackets and rigidly fastened thereto through which said screw bars pass, means on each screw bar for adjusting the position of the bushing with relation to the brackets and means carried by said brackets for holding said screw bars in adjusted position.

EDWARD A. FOSTER.
